UNITED STATES PATENT OFFICE.

ANDREW C. DOUGLASS, OF SONOMA, CALIFORNIA.

TURBINE-PUMP.

1,396,820.

Specification of Letters Patent.

Patented Nov. 15, 1921.

Application filed April 19, 1920. Serial No. 375,069.

To all whom it may concern:

Be it known that I, ANDREW C. DOUGLASS, a citizen of the United States, residing at Sonoma, in the county of Sonoma and State of California, have invented a new and useful Turbine-Pump, of which the following is a specification.

My invention relates to improvements in turbine pumps and its object is to overcome 10 the downward thrust of the shaft.

I accomplish this object by the mechanism illustrated in the accompanying drawings, in which—

Figure 1 represents a vertical section 15 through the pump,

Fig. 2 a horizontal section along line 2—2 of Fig. 1,

Fig. 3 a horizontal section along line 3—3 of Fig. 1,

20 Fig. 4 a horizontal section along line 4—4 of Fig. 1,

Fig. 5 a detail view of the umbrella shaped web and blades, looking at them from underneath,

25 Fig. 6 a detail view of a bearing for the shaft.

Similar numerals refer to similar parts throughout the several views.

1 represents the well casing into which is 30 let the pump casing 2, consisting of an upper part 3 and a lower part 4. The lower end of part 3 and the upper end of part 4 are enlarged and provided with corresponding flanges 6, which are bolted together by bolts 35 7. When joined the two parts 3 and 4 form at their juncture chamber 8 of a shape closely resembling a toy top.

The top of the upper part 3 of the pump casing is covered by a housing 9, consisting 40 of an upper part 11 and a lower part 12. The upper part 11 is umbrella shaped and provided with a flange 14 at the bottom which corresponds to a flange 15 of the enlarged upper end of part 12 of the housing 45 9; by joining the flanges 14 and 15 the chamber 17 is formed. The lower end of part 12 is cylinder shaped and of a diameter considerably larger than that of the pump cas-

ing 2 and is closed at the bottom, an opening 50 being left in the center for pump casing 2 to pass through. The fit of the bottom of part 12 around the pump casing is snug and watertight, as shown at 10. Some distance above its bottom part 12 is provided 55 with a discharge pipe 21. The umbrella shaped part 11 has a central embossed open-

ing 22 to allow the shaft 25 to extend through it. Some distance above said opening the shaft 25 is provided with pulley 33, by means of which it may be connected with 60 any suitable source of power.

The bottom end of shaft 25 runs out into an enlargement of the shape of a toy top. This enlargement is centrally located with reference to chamber 8 of pump casing 2 65 and serves as a hub 24 for three propeller blades 26, which are slightly curved on top, pointed at the bottom, and the outer edges of which run parallel and in close proximity to the curve of the chamber 8. The blades 70 are curved and their concave sides grip the water and carry it upward.

Immediately above but not touching the curved tops of the propeller blades are three stationary baffles 27 with curved bottoms 75 corresponding to the curved tops of the propeller blades 26, which baffles gradually change the curved path of the water along the propeller blades into a straight vertical one. The baffles are rigidly secured to the 80 pump casing and form a centrally located hub 28, in which shaft 25 rotates. The latter is prevented from sliding down by a collar 18 which rotates on steel balls 19 running in a groove 20 formed within the hub 28. 85

Above and near the top of the pump casing the shaft 25 carries a conical shaped hub 30 to which three propeller blades 29 are attached. These resemble in their shape somewhat the blades 26, but are turned upside down, have an opposite lead, and their main working parts reach outside of and below the top of pump casing 2. They turn with the shaft 25, but are intended to work the opposite way from blades 26, that 95 is, while blades 26 carry water upward within pump casing 2, the blades 29 simultaneously force water downward outside the casing 2, but within the housing 11. The outer edges of the blades 29 are curved to 100 follow the lines of the umbrella shaped housing 11 and are connected with each other by a web 31 which also follows the lines of housing 11.

The pump works as follows: The water 105 is lifted by propeller blades 26 into the upper part of pump casing 2 until it reaches the umbrella shaped web 31; here it is engaged by the revolving blades 29 which force the water outward and downward into 110 the passage between pump casing 2 and housing 9. The downward pressure ex-

erted upon the water sets free an equal upward pressure in the water, tending to lift the web 31 and with it the shaft 23, which lifting tendency, provided the sizes of the 5 blades and the two chambers are properly proportioned, is strong enough to balance the downward thrust of the load within the pump casing 2; the blades 29 further serve to give the water an extra impetus, especially where it has to be carried through a 10 line of pipes, as in surface irrigation.

The overcoming of the downward thrust being the principal feature of my invention I do not confine myself to the particular 15 impeller described in the specification. Neither do I confine myself to any particular number of blades.

I claim:

1. In a pump the combination of a casing 20 having a toy top shaped chamber intermediate of its length, a housing having an umbrella shaped top adapted to inclose the upper part of the casing so as to leave a passage between said casing and said housing, a discharge from said passage, a vertical shaft extending centrally through said casing and said housing, means for positioning and driving the same, a water lifting means within the toy top shaped chamber and a 25 means in the umbrella shaped top for forcing water downward into the passage, adapted to be driven by said shaft.

2. In a pump the combination of a casing having a toy top shaped chamber inter- 30

mediate of its length and stationary baffles 35 above said chamber, a housing having an umbrella shaped top adapted to inclose the upper part of the casing so as to leave a passage between said casing and said housing, a discharge from said passage, a vertical shaft extending centrally through said casing and said housing, means for positioning and driving the same, a water lifting means within the toy top shaped chamber and a means in the umbrella shaped top 40 for forcing water downward into the passage, adapted to be driven by said shaft.

3. In a pump the combination of a casing comprising an upper part and a lower part forming a toy top shaped chamber at the 45 junction and having stationary baffles above said junction, a housing comprising an upper and a lower part adapted to water-tightly inclose the upper part of the casing 50 so as to leave a passage between the casing and the housing and to form an umbrella shaped chamber above the same at their junction, and a vertical shaft extending centrally through the casing and housing having a toy top shaped hub at the bottom 55 with a plurality of lifting blades mounted thereon and an umbrella shaped web at the top with a plurality of blades mounted therein adapted to force water downward 60 into the passage between the casing and the 65 housing.

ANDREW C. DOUGLASS.
